Re. 15,956

UNITED STATES PATENT OFFICE.

WALTER W. HEROY, OF BLOOMFIELD, NEW JERSEY.

METHOD AND MEANS FOR SILENCING FLUID IN CONDUITS.

Original No. 1,432,462, dated October 17, 1922, Serial No. 425,085, filed November 19, 1920. Application for reissue filed July 5, 1924. Serial No. 724,496.

To all whom it may concern:

Be it known that I, WALTER W. HEROY, a citizen of the United States, and a resident of Bloomfield, county of Essex, and State of New Jersey, have invented a new and useful Improvement in a Method and Means for Silencing Fluid in Conduits, of which the following is a specification.

This invention relates to mufflers or silencers for escaping fluids, such as gases, water, and the like, and more particularly to a silencer for flush tanks, etc.

An object of the invention is to prevent the production of noise by the movement of fluids in the conduit by which it is carried.

Another object of the invention is to prevent the production of noise by the movement of fluid in the pipe by which it is carried by disintegration and breaking up 20 of the fluid parts through the action of a body movable with the fluid.

A further object of the invention is to prevent the production of noise by the movement of fluid in the pipe by which it is carried and to simultaneously prevent the accumulation of foreign matter by the noise arresting device.

Further objects of the invention will appear as the description proceeds.

The movement of a fluid in a pipe or conduit often causes noise which results from vibrations in the pipe and parts connected therewith, such noise giving great annoyance in the use of many kinds of apparatus in which intermittent movements of the water occur from the opening or closing of the pipe outlet.

A flush-tank may be taken as an example of such apparatus, the noise resulting from the flow in the supply pipe when the tank is flushed. Many means have been devised to obviate the noise which arises after each opening of the flush valve.

It is known that the dynamic force contained in a pent-up fluid when under pressure and static will, when released, be diverted into several portions or component parts of the fluid, exerting separate distinct propelling forces, exhibiting the distribution of energy in direct relation to the configuration or friction of the conduit; and causing a noise in proportion to the energy contained in the dynamics of the fluid, as disintegration takes place upon its release.

Such component parts of the fluid may be 55 regarded as layers enveloping a central core of liquid which layers have a frictional contact with the bore of the pipe and generate in the resulting noise.

In the present invention means, termed 60 "noise arrester" herein, is provided to disintegrate the current of fluid moving in a pipe, so as to oppose and neutralize the vibrations conveyed to the pipe by the moving fluid.

This means consists of a mass of loose granular material confined between two grids in a given section of the pipe, but only partially filling the said section when at rest.

The material is thus free to move or be lifted 70 toward the outlet by the moving current of water, and the mass of such material is so proportioned to the capacity of the pipe-section that the degree of its movement or elevation in the section varies with the velocity of the escaping fluid, and adapts it to

oppose the vibrations of the fluid with uniform effect when moving with different degrees of force. Such opposition disintegrates the outer layers of the water current 80 and greatly reduces the skin friction and noise.

The operation of such a freely movable mass of granular material is found in practice to be essentially different from the operation of a filling of granular material which is not permitted free movement within the pipe-section.

When the fluid is in motion the movable material in the present invention intersects 90 the flow of water at different points, and operates to disintegrate and break up the fluid parts whose dynamic force is convertible into noise if not otherwise diverted.

It will be observed that at each reversal of 95 its movement the granular material is disposed in a different arrangement within the body of the arrester, which produces a very efficient action of the material.

The particles of material in their movements tend to abrade one another sufficiently to rub off any particles of foreign matter which have been deposited upon them.

If the section were entirely filled with 100 granular material it would in the course of time be completely clogged by the deposit of foreign substance from the water flowing through it, and the provision of space for

movement within the arrester thus produces a very useful result in such use of the granular material.

My improvement is shown in Fig. 1 of the drawing applied to a flush-tank; Fig. 2 shows the "noise-arrester" with the outlet-valve closed; Fig. 3 shows the same when the outlet-valve is open and the material raised by the moving current of fluid; Fig. 4 shows the settling of the material after the valve is closed; and Fig. 5 is a diagram illustrating the action of the water in passing through the "noise-arrester." Figs. 2 and 5 are upon a larger scale than Fig. 1. Fig. 6 is a plan of the grid.

A designates the flush-tank in Fig. 1, B the outlet to the closet-bowl which would be controlled by a flush-valve B' as is usual. C is the supply-pipe extended into the body 20 of the "noise-arrester" within the tank, which body is provided upon the top with a tank-valve E controlled by the float F. The body D is represented as of glass to exhibit the movements that occur within the 25 ordinary pipe, which may be made of iron, brass or lead, as required, a section of the supply-pipe in Fig. 2 being clamped by rods G between heads b, b' at its opposite ends, which heads contain grids between which 30 the charge of granular material d is retained.

The head b is connected to the supply-pipe C, and when the tank-valve E is opened by the falling of the ball F the water flows 35 upwardly through the pipe C and arrester-section D, and escapes freely within the tank through the nozzle H.

Fig. 5 represents the section of pipe clamped between the heads b and b', and the 40 flow of fluid through such section is illustrated diagrammatically in this figure. The fluid enters at the bottom, as indicated at the arrow e and flows upwardly through the section to the outlet a.

It is observed that when the fluid is in motion as shown in Fig. 5, its center f advances first and penetrates the granular material, and pushes through it before the 50 particles in contact with the side-walls of the section have materially moved, owing to the skin friction.

The material next the walls of the section is ultimately lifted more or less according to the velocity of the moving current, and when 55 packed in the upper part of the body D as shown in Fig. 3, it forces the flowing water away from the wall of the pipe and breaks the vibrations which would otherwise produce agitations of the pipe D and a corresponding volume of noise.

It is known that the movement of perfectly smooth surfaces upon one another produces no friction and corresponding little noise, but as the water flowing to the tank-valve under high pressure produces normally

a great deal of noise, it is obvious that the water surrounding the central core f is operating like separate layers of component parts f' in rubbing its way through the section D and its outlet, and that the noise is 70 caused by such separate actions and can be arrested by disintegrating the component parts of the current.

The rearrangement of the granular material at each reversal of such material produces a complete disintegration of the water current; and makes the operation of the arrester most effective, while it secures the self-cleansing of the granular material and permits the free passage of any foreign substance through the disintegrated mass. Such foreign material which is too large to pass through the grid c disposed adjacent the outlet end of the arrester is effectively broken up by the successive impacts of the granular 80 material thereagainst.

Fig. 4 shows the gradual settling of the granular material d as the tank-valve is gradually closed, thus changing the 90 position of all its particles.

This is found to be effected in practice by the operation of the "noise-arrester" described (as seen through the glass section), in which the passage of the fluid through the loose granular material absorbs its energy in 95 sufficient degree to overcome the skin friction.

The employment of the granular material in a loose condition effects a very different result from the same material packed closely 100 in a receptacle, or restrained even by its own weight from rising in the section through which the water passes, as the shifting of the granular material brings its particles into new lines of the fluid's movement. This is not effected where the water merely flows through permanent apertures in grids, or permanent apertures between particles of granular material.

My invention is thus a means of muffling 110 the noise of a fluid moving within a pipe, and also affords a self-cleansing construction and arrangement of the granular material.

It is evident that the self-cleansing of 115 the granular material will be effected in whatever position the arrester may be used, as for instance in a horizontal position, as the material being free to move within the body of the arrester would be agitated every 120 time the liquid passed through it, and the particles cleanse one another in settling down upon the lower part of the body when the current ceased.

A "grid" or grating is referred to here- 125 in as less likely to be clogged than a finely perforated screen, but any form of screen may be used that is desired.

The "noise-arrester" may be used in connection with the flushometer or any ap- 130

paratus which it may affect as described herein to restrain or prevent noise.

Although I have specifically described my invention in connection with silencing the noise of water in flush-tanks, it is obvious that the same may be applied to many other devices employing water or fluid. It is also obvious that those skilled in the art may make modifications of the invention, but such as fall within the scope of the appended claims are contemplated by me as forming part of my invention.

Having thus set forth the nature of the invention what is claimed herein is:

15. 1. In the art of muffling the noise of an escaping fluid, the combination, with a pipe conveying such fluid, of a section having grids at both ends, the space between the grids being partially filled with loose granular material free to be lifted as a whole by the current of fluid, such material being self-cleansing by the reversal of its movements.

20. 2. In the art of muffling the noise of an escaping fluid, the combination, with a pipe conveying such fluid, of a section having grids at both ends, the space between said grids being partially filled with loose granular material, and a valve controlling the escape of the fluid adjacent to one of the grids, the mass of said granular material being such as to be lifted as a whole until restrained by the upper grid, and to disintegrate the moving current of fluid and to 35 check its vibrations and thus prevent the agitation of the fluid and the noise resulting therefrom.

30. 3. The muffler constructed in accordance with claim 1, and having the pipe arranged in a vertical position to secure a prompt return of the granular material to its initial position after each movement.

45. 4. A muffler for silencing the noise of an escaping fluid comprising means for conveying fluid and means movable as a whole with said fluid for neutralizing the vibrations conveyed to said first-mentioned means by the moving fluid.

50. 5. A muffler for silencing the noise of an escaping fluid comprising means for conveying fluid and granular means movable as a whole with said fluid for neutralizing the vibrations conveyed to said first-mentioned means by the moving fluid.

55. 6. A muffler for silencing the noise of an escaping fluid comprising a conduit for said fluid, a body of granular material movable as a whole with said fluid and adapted to return to initial position under the action of gravity.

60. 7. A muffler for silencing the noise of an escaping fluid comprising a conduit for said fluid, a body of loose granular material in said conduit and movable as a whole by said fluid, means for arresting the movement of

said granular material but permitting the movement of said fluid therethrough, said material being adapted to return to initial position under the influence of gravity.

8. A muffler for silencing the noise of an escaping fluid comprising a conduit, means for supporting a body of loose granular material in a position to be acted upon by said fluid, said conduit permitting movement of said granular material as a whole therein by said fluid, means for arresting the movement of said granular material, said material being adapted to return to said supporting means upon release of the pressure within said fluid.

15. 9. A muffler for silencing the noise of an escaping fluid, comprising a body of loose granular material, a conduit for said fluid, means for supporting said granular material in the line of flow of said fluid, said conduit permitting movement of said granular material as a whole therein by said fluid, means for arresting the movement of said material but permitting the movement of said fluid therethrough, said material being adapted to return to said supporting means upon release of the pressure within said fluid.

20. 10. The combination with a pipe for conveying fluid, of a section having means for supporting a body of loose granular material at one end thereof, said material being movable as a whole with said fluid, means at the other end of said section for arresting the movement of said granular material but permitting the movement of said fluid therethrough, the mass of the particles of granular material within said section being dependent upon the velocity of the fluid within said section.

25. 11. The combination with a pipe for conveying fluid, of a section thereof containing a body of loose granular material and having means at one end for supporting said material, the size of the particles thereof and the quantity depending upon the velocity of said fluid, said material being adapted to move as a whole with said fluid, means at the other end of said section for arresting the movement of said material, said pipe being so disposed as to permit the return of said material to its initial position to facilitate cleansing of said particles.

30. 12. The combination with a pipe for conveying fluid, of a section thereof containing a body of loose granular material and having means at one end for supporting said material, the length of said section being such as to permit said granular material to move as a body from one position to another in said section, means at the other end of said section for arresting the movement of said body of granular material, and said pipe being so disposed as to permit of the return of said granular material.

by gravity to initial position, whereby the granular material separates and the particles abrade each other to cleanse the same.

13. The method of neutralizing the vibrations conveyed to a pipe by a moving body of fluid which comprises resisting the movement of the fluid by a body freely movable therewith for a predetermined distance and disseminating or disintegrating the fluid parts by a reversal of the movement of said body.

14. The method of neutralizing the vibrations conveyed to a pipe by a moving body of fluid which comprises yieldingly opposing the motion of said fluid by means of a body of granular material movable as a whole a limited distance with said fluid and simultaneously permitting the movement of said fluid within said pipe and through said material.

15. The method of neutralizing the vibrations conveyed to a pipe by a moving body of fluid which comprises disintegrating the fluid parts by yieldingly opposing the motion of said fluid by a body of granular material movable as a whole therewith until said fluid parts are disintegrated and simultaneously therewith permitting the movement of said fluid within said pipe through said material.

16. The method of neutralizing the vibrations conveyed to a pipe by a moving body of fluid which comprises disintegrating the fluid parts by forcing the fluid through

a movable body which is capable of a limited movement with said fluid, said body being returnable through the action of gravity to its initial position upon release of the fluid pressure.

17. The method of neutralizing the vibrations conveyed to a pipe by a moving body of fluid and for preventing the clogging of the passage through which said fluid moves, which comprises passing the fluid through a granular body which is capable of a limited movement against the force of gravity with the fluid, and then permitting gravity to return said granular body to its initial position during which return movement the granular particles abrade each other to remove foreign material.

18. The method of neutralizing the vibrations conveyed to a pipe by a moving body of fluid and for preventing the clogging of the passage through which said fluid moves, which comprises passing the fluid through a granular body which is capable of a limited movement with the fluid against the force of gravity, and then permitting gravity to return the granular material to initial position and simultaneously therewith permitting the particles thereof to abrade each other to remove foreign material.

In testimony whereof, I have hereunto subscribed my name this 25th day of June, 1924.

WALTER W. HEROY.
